(57) **CLAIM**

The ornamental design for a multi-direction adapter, as shown and described.

DESCRIPTION

FIG. 1 is a front elevation view of a multi-direction adapter showing our new design;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken lines in the drawings are included for the purpose of illustrating environment and form no part of the claimed design.
